Inventor:

Matthew Von Culin

UNITED STATES PATENT OFFICE.

MATTHEW VON CULIN, OF BALTIMORE, MARYLAND.

IMPROVEMENT IN MACHINES FOR STRIKING UP SHEET-METAL.

Specification forming part of Letters Patent No. **147,806**, dated February 24, 1874; application filed December 23, 1873.

To all whom it may concern:

Be it known that I, MATTHEW VON CULIN, of Baltimore city, State of Maryland, have invented an Improved Pressing-Machine, of which the following is a specification:

My invention consists, first, in the combination of the follower, that carries the blank-holder, with the reciprocating cross-head, by means of bolts connected to the follower by ball-and-socket joints; and, secondly, in the combination, with the cross-head and plunger, of the cam and crank pin, as hereinafter more clearly set forth.

Figure 1 represents a front view of my improved machine. Fig. 2 is a back view; Fig. 3, a side view. Figs. 4, 5, and 6, represent detached views of the cam and ball-and-socket joints.

A, in Figs. 1, 2, and 3, represents the framework and bed of my machine. Z, Fig. 2, is the driving-pulley; V, the driving-shaft; W, the endless screw which gives motion to the gear-wheel T, which drives the cam D. (See Figs. 1 and 3.) The cam D operates on an anti-friction roller, J, which is carried by lugs on the cross-head K. Said cross-head has long tight bearings B B, and carries two bolts running vertically through it, and adjustable thereto by means of nuts on the top and bottom of the cross-head, the other ends of the bolts being attached to the follower H by the ball-and-socket joints S S, of which Fig. 4 is a vertical section. a a, b b, and h, Fig. 1, represent a vertical section of the die, blank-holder, and plunger. e e is the holding-surface of the die, and o o the holding-surface of the blank-holder; h, the plunger. The holding-surface of the die and diameter of the blank being the same, the blank must of its own gravity find its correct position in the die. The holding-surface and tapering sides of the blank-holder fit exactly the holding-surface

and flaring sides of the die. The follower H runs sufficiently loose in the guides B B to allow the blank-holder to adjust itself to the blank by means of the ball-and-socket joints S S and tapering sides of the blank-holder a a with the flaring sides of the die b b. The anti-friction roller is held in position against the cam by means of springs, levers, or other suitable means. The crank-pin f, Fig. 1, is set opposite the center, N, Figs. 1, 5, and 6, of the circular part of the cam, from L to L. The yoke c, and arm J which carries the plunger, are given a reciprocating motion by the crank-pin f, which travels from c to c, in the slots y y, as the cam revolves. The holes d, g, and k, Fig. 6, or the slot M, Fig. 5, (or by keying the cam or crank off a common center in other machines not here described,) are for moving the crank-pin off the center N. The plunger h continues its downward motion after the blank-holder a strikes the blank, a proportionally longer stroke being given if I move the crank-pin f off the center N, thus enabling me to press a deeper piece in proportion to the throw of the press than has yet been accomplished. The arm J is guided by a groove in cross-head K and a cap, F.

What I claim, and desire to secure by Letters Patent of the United States, is—

1. The combination of the follower that carries the blank-holder with the reciprocating cross-head K, by means of bolts connected to the cross-head by ball-and-socket joints, as specified.

2. The combination, with the cross-head K and plunger J, of the cam D, and adjustable crank-pin f, as specified.

MATTHEW VON CULIN.
